UNITED STATES PATENT OFFICE.

WILLIAM DUNCAN THOMPSON, OF TOOGOOLAWAH, QUEENSLAND, AUSTRALIA.

CHAIN TIGHTENER.

Application filed July 2, 1923. Serial No. 649,139.

To all whom it may concern:

Be it known that I, WILLIAM DUNCAN THOMPSON, subject of the King of Great Britain, residing at Toogoolawah, Queensland, Australia, have invented certain new and useful Improvements in Chain Tighteners, of which the following is a specification.

In the past it has been a somewhat difficult matter to strain non-skid chains onto motor car wheels, especially when the car has been stuck up in a soft place. The object of this invention is to provide a mechanical strainer which makes the operation comparatively easy. It will be seen from the description, which follows that the appliance is adaptable for use in straining the wires of fences as a lifting jack, and for other like purposes.

In carrying out my invention I articulate two levers together by two links arranged in such a manner that a comparatively great strain is obtained by the movement of a single lever.

In order that my invention may be better understood I will now describe same with the aid of the accompanying drawings, in which—

Fig. 1 shows a simple arrangement mid open and part broken off.

Fig. 2 shows the device closed and a locking device thereon.

Fig. 3 shows the device mid open and with an alternative locking device.

Fig. 4 shows the device full open.

Fig. 5 shows the invention as applied to a lifting jack.

The lever A is formed at one end (not shown) as a handle or grip and the other end B is provided with a hole C for attaching the hook C¹ for engaging one end of a non-skid chain. A link D is pivoted at E to the lever A, and nearer to the handle the link F is pivoted at G. These links D F, which are of unequal length, and which cross each other, are pivoted at H and J respectively to a lever K. This lever K is also fitted at the end with a hole L for attaching the hook L¹.

In Figs. 1 and 4, I show the levers A and K provided with a pin M for holding them in desired positions, which pin engages the hole N in the link F and one of the holes P in the link D. (See Fig. 1.)

In Fig. 2 the levers A and K are held in the desired position by the pawl Q on the lever A engaging the toothed sector R on

the end of the link F. A spring S keeps the pawl Q normally in engagement with the sector R.

In Fig. 3, the levers A and K are held in the desired position by the pawl Q on the lever A engaging the toothed sector R secured on the link F. The clip T on the lever A guides the sector R and the spring S keeps the pawl Q normally in engagement with the sector R.

When it is desired to use the device for straining, wire toggle grips of ordinary construction or other devices would be attached to the levers A and K instead of the hooks C and L.

When the device is to be used as a lifting jack, shoes U V would be fitted to the levers A and K respectively.

Although I do not wish to bind myself to any particular measurements of the various parts nor to the distance between the various centres, I give the following information by way of guidance:—

Centres C to E of lever A one and one half inches.

Centres E to G of lever A one and one half inches.

Centres E to H of link D three and one half inches.

Centres G to J of link F three and three quarter inches.

Centres H to J of lever K one and one half inches.

Centres J to L of lever K three quarters of one inch.

The details of construction may be varied to suit the ideas of manufacturers.

The operation of my invention is as follows:—

Supposing the device is being used for straining non-skid chains on to motor vehicular wheels, the hooks C¹ L¹ are caused to engage the ends of such chains, the hook ends C¹ and L¹ being at the extreme limit of their travel as shown in Fig. 4. On the lever A being moved, it pivots at C¹, drawing over the links D and F. The link F pivots on G and draws on the lever K, which pivots at H on the link D. At the same time, the action of the links D F is such that the link D seems to force the end H away from the lever A causing it to swing on the pivot J of the link F and thus forcing the hook L¹ towards the hook C¹. The result is that a very powerful leverage is obtained.

Having now particularly described and

ascertained the nature of my said invention and in what manner the same is to be performed, I declare that what I claim is:—

- 5 1. A pushing and pulling implement including a long manually operated lever provided at one end with means to engage the object to be manipulated, a short lever, crossed links arranged near the lower end of the long lever, each of said links having one of its ends pivotally connected to the long lever and its other end pivotally connected to the short lever, one of said links being connected to the upper end of the short lever, means 25 at the other end of the short lever to engage the object to be manipulated, and means for locking said links in various positions relatively to each other.
- 10 2. A pushing and pulling implement including a long manually operated lever, a short lever arranged adjacent to the lower end of the long lever, crossed links pivotally connected to both of said levers, and connecting elements carried by the lower ends 35 of both levers to engage the parts which are to be moved relatively to each other.
- 15 3. A pushing or pulling implement including a long manually operated lever, a short lever arranged adjacent to the lower end of the long lever, crossed links pivotally connected to both of said levers, and connecting elements carried by the lower ends 30 of both levers to engage the parts which are to be moved relatively to each other.

In testimony whereof I affix my signature.

WILLIAM DUNCAN THOMPSON.
